UNITED STATES PATENT OFFICE.

GEORGE I. LEONARD, OF CHICAGO, ILLINOIS, ASSIGNOR TO LEONARD PUMP AND MOTOR CO., OF CHICAGO, ILLINOIS, A CORPORATION OF MAINE.

ELECTRICALLY-CONTROLLED APPARATUS.

1,296,976.

Specification of Letters Patent. Patented Mar. 11, 1919.

Application filed January 29, 1917. Serial No. 145,111.

To all whom it may concern:

Be it known that I, GEORGE I. LEONARD, a citizen of the United States, residing at Chicago, in the county of Cook and State of Illinois, have invented a new and useful Improvement in Electrically-Controlled Apparatus, of which the following is a specification.

My invention relates more particularly to 10 electrically-controlled apparatus suitable for use in connection with refrigerating systems operating automatically through thermostatic means, to perform the refrigerating function, though certain features of the 15 invention may be used in other connections, it being my intention to claim all the features of my invention for all the uses to which they may be placed.

Some of my objects, specifically stated, 20 are to provide improved electrically-operated means whereby the minimum amount of current may be used to control the operation of the electrically-controlled mechanism through the medium of which a power-element, as for example, a pump which compresses the refrigerant, is operated. Another object is to provide for the automatic cutting out of the contact-making and breaking device, usually a thermostat, in the case 25 of a refrigerating system, immediately following its operation, and the effective energization of the mechanism controlled thereby after said device is cut out by supplying the latter with the current sufficient to energize it, and thus avoid the traversing of 30 said device, by a current of such intensity, as would impair said device, or its effective operation. Another object is to provide for the rendering inoperative the power-device, 35 as for example, the motor which drives the refrigerant-compressing pump, in the event of the failure of the supply of fluid, as for example, water for condensing the compressed refrigerant coöperating with the power-device. Another object which relates 40 to the use of my invention in a refrigerating system, is to provide means which operate positively and effectively to automatically regulate the supplying of refrigerant to the 45 coil, or chamber, to be cooled for maintaining the desired temperature therein; and other objects, as will be manifest from the 50 55 following description.

Referring to the accompanying drawings, Figure 1 is a plan view of a portion of a

refrigerating system in which my invention is incorporated, certain portions of the mechanism therein shown being illustrated in section. Fig. 2 is a section taken at the line 2 on Fig. 1 and viewed in the direction of 60 the arrow. Fig. 3 is a section taken at the line 3 on Fig. 1 and viewed in the direction of the arrow. Fig. 4 is a section taken at the line 4 on Fig. 1 and viewed in the direction of the arrow. Fig. 5 is a broken section 65 taken at the line 5 on Fig. 3 and viewed in the direction of the arrow. Fig. 6 is a section taken at the line 6 on Fig. 3 and viewed in the direction of the arrow. Fig. 7 is a section taken at the line 7 on Fig. 1 and 70 viewed in the direction of the arrow. Fig. 8 is a section taken at the line 8 on Fig. 1 and viewed in the direction of the arrow. Fig. 9 is a plan view of another portion of the refrigerating system. Fig. 10 is a view 75 in elevation of the structure shown in Fig. 9, this view showing the structure as viewed from the end thereof lowermost in Fig. 9. Fig. 11 is a section taken at the line 11 on Fig. 9 and viewed in the direction of the arrow. Fig. 12 is a section taken at the line 12 on Fig. 10 and viewed in the direction of the arrow; and Fig. 13, a view, in the nature of a diagram, showing the complete refrigerating system with the various electrical circuits and electrical apparatus by which the operation of the pump for compressing the refrigerating medium, is automatically controlled.

Referring first, to the refrigerating apparatus disclosed, and in connection with which I have chosen to illustrate my invention, it may be stated as a preface to the following description that the system shown is of a type involving a refrigerating coil located 90 in the chamber to be cooled or in the desired close proximity thereto, a pump in communication with the discharge-end of the refrigerating coil and adapted to receive the refrigerant in gasified condition after it 95 has performed its work in the refrigerating coil, and compress the same to liquefy it, the refrigerant so liquefied passing into an expansion-valve which opens into the inlet-end of the refrigerating coil, the pump being 100 operated by any suitable motive device, the operation of which is controlled electrically through the medium of a thermostat located, preferably, in the refrigerating chamber.

Referring to Fig. 13 the refrigerating 110

chamber above referred to, and which may be a chest, or the like, is represented at 20, and the refrigerating coil, located therein, at 21. A pipe 22 leads from the discharge 5 end of the coil 21 to the suction-side of a pump 23 which may be of any desirable type, as, for example, that involving intermeshing gears, the pump 23, which in the arrangement illustrated, is operated by an 10 electric motor 24, discharging into a condenser-chamber 25 cooled by water passed from a pipe 26 through a coil (not shown) in the chamber 25 and discharged from this coil through a pipe 27, the water being supplied as hereinafter described, the condenser-chamber being so constructed as to serve 15 as a receptacle for the liquefied refrigerant.

The outlet-end of the condenser-chamber 25 connects with a pipe 28 provided with 20 the usual expansion-valve 29 and communicating with the inlet-end of the coil 21, the arrangement of the parts just described being such in accordance with general practice that when the pump 23 is driven the 25 refrigerating medium, such as sulfur dioxide is sucked in gasified condition from the coil 21, into the pump 23 from which it discharges in compressed condition into the condenser 25 where it becomes liquefied and 30 is forced into and through the expansion valve 29 into the coil 21, where it expands and performs the refrigerating function, the compressed refrigerant continuing to discharge through the expansion valve 29 into 35 the coil 21 until the pressure at opposite sides of the valve 29 is equal, this result occurring only during the periods when the pump is idle under the control of the electrically-operated mechanism hereinafter 40 described.

As usual in refrigerating systems where the operation of the pump for the refrigerant is controlled through the making and breaking of electrical contacts, a thermo- 45 static device is provided, preferably, in the refrigerating chamber 20, this device, shown diagrammatically, being represented at 29 and involving a current-carrying member 30 so constructed, in accordance with common practice, that its outer end is caused 50 to move alternately into electrical contact with stationary contacts 31 and 32, under changes in temperature, of the surrounding atmosphere, the thermostat in the particular arrangement illustrated being so constructed and arranged as to engage with the contact 32 when the temperature in the chamber 20 exceeds the desired amount and 55 to engage the contact 31 when the temperature in the chamber 20 becomes lowered beyond a predetermined amount.

In the particular system illustrated, which is designed for use with alternating current, the thermostat 29 serves to establish the desired circuits for controlling the operation 60

of the motor 24 under variations in temperature in the chamber 20, through the medium of the electrically-operated devices of which the following is a description.

Referring particularly to Fig. 1 of the drawings, 33 is a rock-shaft mounted in bearings 34 rising from a base 35 of insulating material, this shaft being equipped with an arm 36 provided at its outer end with a block 37 of insulating material carrying a metallic yoke-shaped member 38 which is adapted, when the shaft 33 is in the position illustrated in Figs. 1, 2 and 3, to be wedged in between a pair of upright spring-contact fingers 39 and 40 secured, as by screws 41 and 42 to a block 43 of insulating material secured to a plate 35^a of insulating material mounted on the base 35, the device just described constituting the switch for controlling the operation of the motor 24, as hereinafter described. The shaft 33 is also provided with a crank-arm 44 formed of two sections 45 and 46, the section 45 being preferably of metal and the section 46 which is connected with the section 45, as by a pin 47 to be rigid therewith, being formed of insulating material. The lower extremity of the crank-arm 44 is provided with a pin 48 with its left-hand end as viewed in Fig. 1, of general V-shape in cross-section, as represented in Fig. 3, this end of the pin co-operating with the movable member 49 of a switch-device, for actuating said member in opposite directions, for the purpose hereinafter explained. The movable member 49 is in the form of a yoke at which it has pivotal support on a pin 50 mounted in a pair of spaced brackets 51 and 51^a secured to, and rising from, the plate 35^a, said yoke-member being provided with the contact arms 52, 53, 54 and 55, the arms 52 and 53 being in alinement, and the arms 54 and 55 in alinement as represented in Fig. 1, and the members forming each pair of the arms thus provided, extending at an angle to each other, as represented in Fig. 3. The plate 35^a is provided with four switch-contacts 56, 57, 58 and 59, each of these contacts being formed of a pair of spring-fingers, as represented of the contacts 56 and 59 in Fig. 6. The contacts 56, 57, 58 and 59 are so arranged, relative to the movable contact 49 that the arms 52, 53, 54 and 55 will be in position to engage them, respectively, in alternation. Thus when the arms 52 and 55 engage with the contacts 56 and 59 the arms 53 and 54 will be out of engagement with the contacts 57 and 58 and vice versa, the purpose being to electrically connect together, the contacts 56 and 59 when the movable member 49 is in one position and to connect together the contacts 58 and 57 when the movable member 49 is in its other position, these stationary contacts being so constructed and ar- 105 110 115 120 125 130

ranged as shown as to permit the arms or blades of the movable member 49 to enter between them and disengage therefrom in the shifting of the member 49.

- 5 The wings 52 and 53 have shouldered portions 60 and 61, respectively, which extend alternately into the path of movement of the pin 48 when it is oscillated by the rocking of the shaft 33. The pin 48 operates to initially move the member 49, the movement of the latter being completed, to make the electrical contacts above stated, by the action of a spring 62 connected at its upper end with a pin 63 vertically adjustable in an 10 apertured portion 64 of the bracket 52 and held in adjusted position by a set-screw 65, the lower end of this spring engaging a notch 66 in the upturned portion 67 at one end of the member 49, this notch being so 15 positioned that it is in line with the pin 50, whereby under the downward pressure exerted by the spring 62, as soon as the member 49 has been rocked a slight distance beyond central position in either direction the 20 spring forcibly completes the swinging movement of the member, moving its arms into electrical engagement with the arms 55 and 56 or 54 and 57, as the case may be, stops 68 and 69 arranged below the arms 25 52 and 53 operating to limit the turning movement of the member 49 in both directions. The shaft 33 is oscillated, in the particular construction illustrated, to move the arm 37 into and out of engagement with the 30 contacts 39 and 40 to make and break the circuit through the motor 24, and to move the switch device formed of the arms 52, 53, 54 and 55 into and out of engagement with the coöperating contact-members 56 to 35 59, inclusive, respectively, as hereinbefore described to electrically connect together, alternately, the contacts at opposite sides of this switch device, by means of solenoid mechanism comprising a pair of coils 70 and 40 71 secured to the base 35 at opposite sides of the shaft 33; and cores 72 and 73 vertically reciprocable in the coils, respectively, and pivotally connected at their upper ends, through the medium of links 74, with arms 45 75 secured to and extending laterally from the shaft 33, to which arms the links 74 are pivotally connected, the arrangement being such that when the coils 70 and 71 are alternately energized the shaft 33 will be oscillated.
- 50 Mounted on a base 76 of insulating material, is a pair of vertically-disposed solenoid devices 77 and 78, each of these solenoid devices comprising a yoke-member 79 of magnetic material secured to the base 76, as through the medium of a strap 80; a pair of coils 81 and 82 arranged in spaced relation and encircling the arms 79^a of the yokes 79, respectively, the coils 81 being so constructed as to present relatively greater resistance
- 55 to the passage of electrical current therethrough, than the coils 82; and armatures 83 and 84 coöperating with the cores 79^a of the respective solenoid devices 77 and 78. The armatures 83 and 84 are mounted on 70 arms 85 and 86, respectively, of non-magnetic material, pivotally supported at their adjacent ends on a horizontally-extending pin 87^a carried by the base 76, the construction and arrangement of these parts being 75 such that the armatures and the arms carrying them are free to rock independently of each other on the pivot 87 and under the action of gravity normally occupy the position illustrated in Fig. 9, in which position 80 they bear against adjustable stop-devices 87 and 88, respectively, carried by the base 76, the arms 85 and 86, carrying contact-members 89 and 90, respectively, having lugs 91 and 92 of insulating material. The contact-members 89 and 90 coöperate with sets of contacts, arranged at opposite sides of the cores just described, and involving a contact-member 93 rising from the base 76, a contact-member 94 of springy material secured to the base through the medium of a screw 95 and normally engaging the contact 93 as represented in Fig. 9, a contact 96 secured to the base by the screw 95 and electrically connected with the contact 94, and 95 contacts 97, 98 and 99 of the same construction and arrangement as described of the contacts 93, 94 and 96, respectively, the contacts 98 and 99 being secured to the base 76 and in electrical contact with each other by 100 means of a screw 100. The lugs 91 and 92 are so related to the contact devices just described that when the armatures connected therewith are drawn upwardly by energizing the solenoids 77 and 78 these lugs will 105 move the contacts 94 and 98 out of engagement with the contacts 93 and 97, respectively, and the arms 89 and 90 will move into electrical contact with the contacts 96 and 99, respectively.
- 110 According to the preferred illustrated embodiment of my invention the control mechanism for the motor 24 also involves the provision of a contact-member 101 secured to the plate 35^a and having extremities 102 and 103, a stationary contact 104 secured to the plate 35^a, and movable contacts 105, 106 and 107 adapted to coöperate with the extremities 102 and 103 of the contact 101 and with the contact 104, respectively. These movable contacts are provided on the opposite sides of a block 108 of insulating material which carries a guide-finger 109 traveling in a groove 110 in the plate 35^a, this block being mounted on the end of a rod 111 connected with a piston 112 reciprocable in a cylinder 113, a coiled spring 114, confined between a wall of the piston 112 and a wall of the cylinder 113 tending to shift the piston 112 and the parts carried thereby to the 115 120 125 130

right in Fig. 1. The mechanism just described is provided for the purpose of effecting the breaking of the circuit through the motor 24, in the event that the motor is 5 running, or preventing the establishment of the circuit through the motor, should for any reason the water supply to the condenser-chamber 25 be discontinued or so reduced as to render the continued operation 10 of the apparatus undesirable. To this end the right-hand end of the cylinder 113 in Fig. 1 is connected with a pipe 115 which opens into a pipe 116 leading from the source of water supply (not shown), for supplying 15 water to the condenser-chamber 25 through the pipe 26. So long as pressure continues in the pipe 116 the resistance of the spring 114 is overcome and the piston with the parts carried thereby is maintained in the 20 position illustrated in Fig. 1 wherein contact 105 engages the contact-extremity 102 and the contact 107 engages the contact 104. At this stage of the description of the apparatus shown, it may be stated that the 25 pipe 26 opens into a valve-casing 117, shown as secured to the base 35, this casing containing a rotatable valve 118 connected at its stem 119 with the shaft 33 through a coupler 120 and serving, through a port 121 therein, 30 to control communication of the pipe 26 with a pipe 122 connecting with the pipe 116. The parts described are so arranged that when the shaft 33 is in a position wherein the motor-switch formed of the contacts 39 35 and 40 is closed, the valve 118 will be open, thus establishing communication between the pipe 116 and the pipe 26, whereby water for the purpose of producing condensation of the gaseous refrigerant discharged into 40 the chamber 25 by the operation of the pump in the chamber 23, will be caused to flow through the coil in the chamber 25 and discharge through the pipe 27, while the motor 24 is operating, the rocking of the shaft 45 33 to a position in which the motor-switch referred to is opened, moving the valve 118 to closed position.

Referring more particularly to Fig. 13 the 50 circuit connections in the particular construction illustrated, are as follows: The main line wires leading from a source (not shown) of alternating current, are represented at 123 and 124, the wire 123 being in electrical contact with the arms 85 and 86 and 55 also in electrical contact with the member 30 through the medium of a wire 125. The wire 124 connects with one of the terminals of the coil 70, the other terminal of which connects by a wire 126 with the stationary 60 contact 57, the wire 124 being connected with a wire 127 which connects with one of the terminals of the coil 71, the other terminal of this coil being connected with the contact 56 through the medium of a wire 128. 65 A wire 129 connects with the stationary con-

tact 31 of the thermostat and with one of the terminals of the high resistance coil 81 of the solenoid 77, the other terminal of this coil connecting by a wire 130, with the contact 93. A wire 131 connects the contact 32 70 of the thermostat with one of the terminals of the high resistance coil 81 of the solenoid 78, the other terminal of this coil being connected by a wire 132 with the stationary contact 97. One terminal of the low resistance 75 coil 82 of the solenoid 77 connects by a wire 133 with the contacts 94 and 96, the other terminal of this coil being connected by a wire 134 with the contact 105 on the rod 111. One of the terminals of the low resistance 80 coil 82 of the solenoid 78 connects by a wire 135 with the contacts 98 and 99, the other terminal of this coil being connected by a wire 136 with the contacts 106 and 107 on the rod 111, the contact 104 being 85 connected by a wire 137 with the contact 58, and the contact 101 being connected by a wire 138 with the contact 59. By preference, condensers 139 and 140 are interposed in wires 141 and 142, respectively, the wire 141 90 connecting at one end with the contacts 94 and 96 and at its opposite end with the contact 93, and the wire 142 being connected at one end with the contacts 98 and 99 and at its opposite end with the contact 97, for 95 the purpose of preventing undue sparking at the contacts controlled by the armatures 83 and 84. The motor circuit comprises the main line wires 143 and 144 which lead from any suitable source of current supply (not 100 shown), the wire 143 being connected with the contact 39 and the wire 144 with the terminal 145 of the motor 24, and a wire 146 connects with the other terminal 147 of the motor and with the contact 37. 105

In the diagram above referred to the parts of the structure are in the position they assume when the movable member 30 of the thermostat is in electrical contact with the contact 32, produced by the rise of temperature in the chamber 20 above that desired to be maintained in this chamber, and after the motor 24 has been set into operation for compressing the refrigerant preparatory to its introduction into the coil 21 produced by 115 the circulation of the refrigerant in the system, brought about by the operation of the pump. According to this condition, the motor-switch, including the members 37 and 39, is closed, the contacts 56 and 59 are connected together through the switch-member carried by the shaft 33, the contacts 57 and 58 are out of electrical engagement, the armatures 83 and 84 are in their lowermost position in which the contacts 93 and 94 engage and the contacts 97 and 98 are in electrical contact, the contact mechanism carried by the rod 111 is in the position illustrated, wherein the contacts 102 and 105 and the contacts 104 and 107 are, respec- 120 125 130

tively, in engagement with each other, owing to the pressure of the water in the chamber 113, and the water is flowing through the pipe 116, pipe 26 and condenser-chamber 25 and out through the pipe 27 to cool the gas discharged into this chamber under the action of the pump operated by the motor 24 which is running. The operation of the pump as stated produces the circulation of the refrigerant in the system shown, the discharge of the liquid-refrigerant into the coil 21 being effected through the expansion-valve 29, and this operation of the pump continues until the temperature in the chamber 20 drops to such a degree therein as to cause the movable member 30 of the thermostat to move out of electrical contact with the contact 32 and into engagement with the contact 31. As soon as the last-referred-to action has taken place the motor 24 is caused to stop and the supply of water to the condenser-chamber 25 is arrested, by establishing the following circuits:

From the wire 123 to wire 125, movable contact 30, contact 31, wire 129, coil 81 of solenoid 77, wire 130, contact 93, contact 94, wire 133, low resistance coil 82 of the solenoid, wire 134, contact 105, contact 101, wire 138, contact 59, thence through the movable switch-member of which the arms 52 to 55, inclusive, are parts, to contact 56, wire 128, coil 71, wire 127, and back through wire 124.

The effect of thus energizing the solenoid 77 is to raise the arm 85 to break electrical contact between the contacts 93 and 94 and establish electrical connection between the contacts 89 and 96, for a purpose hereinafter described, in the particular arrangement illustrated the circuit breaking at 93 and 94 before a circuit is established at 89 and 96. It may here be stated that while the current which is thus caused to traverse the coils 81 and 82 also traverses the coil 71, the coils 81 and 82 are so wound as to produce a combined resistance sufficient to prevent the coil 71 from being energized to the required extent for rocking the shaft 33 from the position shown in Fig. 1, wherein the motor-switch is closed, to a position in which the motor-switch is open, though the resistance afforded by the coils 81 and 82 is not sufficient to prevent the operation of the armature 83, as stated. In the movement of the armature 83 as above stated, by reason of the disengagement of the contacts 93 and 94, the circuit in which the high resistance coil 81 of the solenoid 77 and the contact 31 are interposed, is broken, and by reason of the movement of the contacts 89 and 96 into engagement with each other a circuit in which the low-resistance coil 82 is interposed, is established as follows:

From wire 123 through arm 85, contact 89,

contact 96, wire 133, coil 82 of solenoid 77, wire 134, contact 105, contact 101, wire 138, contact 59, across to contact 56, wire 128, coil 71, wire 127 and back through wire 124. The current thus continues to traverse the coil 71, and by cutting out the coil 81 of solenoid 77 resistance in the circuit in which the coil 71 is interposed is so reduced (the coil 82 being wound to effect this result), as to permit sufficient current to traverse the coil 71 to actuate the shaft 33. Actuation of this shaft, as stated, operates to open the switch for the motor 24 by swinging the member 37 out of engagement with the contacts 39 and 40 and simultaneously therewith breaks the circuit between the contacts 59 and 56 and electrically connects together the contacts 57 and 58, the actuation of the shaft 33, as stated, also turning the valve 118 to a position in which the supply of water to the condensing chamber 25 is arrested. Inasmuch as the energization of the solenoid 77 is dependent on the contacts 59 and 56 being electrically connected together, the actuation of the shaft, as stated, automatically breaks the circuit through the solenoid coil 82 and thus the armature 83 drops to normal position (Fig. 13), whereupon the contacts 89 and 96 disengage and the contacts 93 and 94 move into electrical contact with each other. The parts of the apparatus remain in the positions just described until the temperature in the chest 20 rises to such a degree that the movable member 30 of the thermostat shifts into engagement with the contact 32, whereupon the solenoid 78 is energized through the medium of the two coils 81 and 82 thereof to raise the armature 84 which automatically cuts out the coil 81 and the thermostat, whereupon the current which then traverses the coil 70, rocks the shaft 33 to a position in which the motor-switch is closed and electrical contact is again established between the contacts 56 and 59, the circuits established in this operation being as follows:

From wire 123 to 125, contacts 30 and 32, wire 131, through coil 81 of solenoid 78, wire 132, contacts 97, 98, wire 135, coil 82 of this solenoid, wire 136, contact 107, contact 104, wire 137, contact 58, thence across to contact 57, wire 126, coil 70 and back through wire 124.

When the armature 84 rises under the action of the solenoid 78 it breaks electrical contact between the members 97 and 98, thus cutting out the coil 81 and the thermostat and makes electrical connection between the contacts 90 and 99, the current then flowing from wire 123 through arm 90, contact 99, wire 135, coil 82, wire 137, contacts 107, 104, wire 137, contacts 58, 57, wire 126, coil 70 and wire 124, thus energizing the coil 70 sufficiently to rock the shaft

130

33 to the position illustrated in Fig. 13, in which the motor-switch is closed, the motor starts running, the valve 118 is opened, and electrical contact between the contacts 57 and 58 is broken and electrical contact between the contacts 56 and 59 is established. From the above description it will be understood that each time the movable contact 30 moves into engagement with the contacts 32 and 31, the motor will be started or stopped, and likewise the supply of water turned on or shut off, respectively, to control the temperature in the chest 20. Furthermore, the only current that flows through 15 the thermostat is that which traverses both of the coils of the solenoid 77 or 78, as the case may be, and as the amount of current required to energize these solenoids sufficiently to draw their armatures to a position 20 in which the contacts controlled thereby are operated, as hereinbefore described, is relatively slight, the combined resistance of these coils may be relatively high and thereby minimize danger to the contacts 31 and 25 32 from the heating or corroding of the same and from adhesion of the movable member 30 thereto, which sometimes occurs in the use of thermostats where relatively high currents traverse these contacts.

30 Furthermore, inasmuch as the operation of the respective solenoids 70 and 71 for opening and closing the motor-switch, simultaneously breaks the circuit through the one of said solenoids which is operating, the 35 traverse of the current from the wires 123 and 124 is momentary only, thus minimizing the amount of current required to operate the apparatus.

The contact mechanism, portions of which 40 are carried by the rod 111, as hereinbefore stated, serves to afford means which operate automatically, should the supply of water to the pipe 116 cease or become so reduced in pressure as not to be available for use, 45 to prevent the actuation of the solenoid 70 for closing the motor circuit, should the shaft 33 be in a position in which the motor-switch is open, or actuate the solenoid mechanism 71 to open the motor-switch, when 50 the shaft 33 is in a position in which this switch is closed, the circuits by means of which this operation is accomplished being as follows:

Assuming the apparatus to be in the position illustrated in Fig. 13, in which the motor 24 is running, the movement of the rod 111 to the right in this figure will cause the contact 106 to engage the contact 101 at the extension 103, disengaging the contact 104 55 from the contact 107 and the contact 105 from the contact 102, the current then passing through wire 123, wire 125, through contact-member 30, contact 32, wire 131, coils 81 of solenoid 78, wire 132, contacts 97 and 60 98, wire 135, coil 82, wire 136, contact 106,

contact 101, wire 138, contact 59, thence through the movable part of this switch to contact 56, wire 128, coil 71 and wire 127 to wire 124. Both of the coils 81 and 82 of this solenoid will be energized, which raises 70 the armature 84, thereby cutting out the coil 81 and causing a current to traverse the coil 71, of such intensity as to actuate the latter and rock the shaft 33 to a position in which the motor-switch is opened, whereupon 75 on the contacts 57 and 58 become bridged across by the movable contact-member co-operating therewith. Should the water supply fail when the motor-switch is open and the temperature in the chest 20 rises to a 80 degree which causes the chamber 30 to engage the contact 32, no current can traverse the coil 70 to move the motor-switch to closed condition, as the circuit between the contacts 104 and 107 is broken. There is 85 thus provided automatically operating means which positively operate to prevent the operation of the pump when the supply of condensing medium to the apparatus is discontinued or reduced beyond the necessary requirements and thereby dangers which would result from the operation of the apparatus with an insufficient supply of condensing medium, are avoided.

It is desirable that the coils 81 and 82 of 95 solenoids 77 and 78 be so wound that the current traverses them in the same direction, as distinguished from traveling through one of these coils in one direction and the other of the coils in another direction, in order 100 that the current supplied to these coils produce the maximum magnetic effects.

Where the apparatus is to be actuated by direct current, the apparatus involving the solenoids 77 and 78 would be dispensed with, 105 and the contact 31 would be directly connected with the wire 134 and the contact 32 directly with the wire 136, under which conditions the engagement of the movable contact-member 30 with the contact 31 would 110 energize the coil 71, to move the shaft 33 to a position in which the motor-switch is opened, without first effecting the circuit-changing operation, as explained of the construction shown in Fig. 13, and when the 115 movable contact 30 engages the contact 32 the coil 70 will be directly energized to close the motor-switch without the preliminary circuit-controlling operation required in the case of the arrangement shown in Fig. 13. 120

What I claim as new and desire to secure by Letters Patent is:

1. The combination of an electrical circuit, a circuit-making-and-breaking device in said circuit, a relay-operated switch device in said circuit, an electrically-controlled element in said circuit, a second circuit in which said element and a part only of the resistance in said first-named circuit are interposed, means actuated by the energiza- 130

tion of said switch device to break said first-named circuit and cut out said circuit-making-and-breaking device and a portion of the resistance in said last-referred-to circuit,
5 said electrically controlled element being constructed and arranged to be non-operative by the current traversing said first-named circuit with the full resistance interposed therein and be operative when the
10 said portion of the resistance is cut out, and means operated by the actuation of said electrically-controlled element for breaking said second-named circuit.

2. The combination of an electrical circuit, a circuit-making-and-breaking device in said circuit, a solenoid device formed of resistance elements both of which are normally in said circuit when the latter is closed by said first-named device, an electrically-controlled element in said circuit, a second circuit in which said last-named element and one of said resistance elements are interposed, means actuated by the energization of said solenoid device to break said first-named circuit to cut out said first-named device and the other of said resistance elements and close said second circuit to actuate said electrically-controlled element, and means actuated by said electrically-controlled element for breaking said second circuit.

3. The combination of an electrical circuit, a circuit-making-and-breaking device in said circuit, an electrically-operated switch device in said circuit, an electrically-operated element in said circuit, a second circuit in which said electrically-operated element and a part only of the resistance in said first-named circuit is interposed, means 35 actuated by the energization of said switch device to break said first-named circuit and cut out said first-named device and close said second circuit, said electrically-operated element being constructed and arranged 40 to be non-operative by the current traversing said first-named circuit with the full resistance interposed therein and be operative 45 when the said portion of the resistance is cut out, and means operated by the actuation of said electrically-operated element for breaking said second-named circuit. 50

4. The combination of an electrically-controlled member, a switch device for controlling the actuation of said member, electrically-controlled mechanisms for opening and closing said switch device, electrically-controlled switch-devices, an electrical circuit in which one of said electrically-controlled switch-devices and one of said electrically-controlled mechanisms controlling the position of said first-named switch device are interposed, means for closing said circuit, a second circuit in which said last-referred-to electrically-controlled mechanism and a portion only of the resistance in said

first-named circuit, are interposed, a third circuit in which the other of said electrically-controlled switch-devices and the other of said electrically-controlled mechanisms controlling the position of said first-named switch-device, are interposed, means for closing said last-named circuit, a fourth circuit in which said last-referred-to electrically-controlled mechanism controlling said first-named switch device and a portion only of the resistance in said first circuit, are interposed, and means actuated by the energization of said electrically-controlled switch-devices, respectively, to break said first and third circuits, respectively, and close said second and fourth circuits, respectively. 70 75 80

5. The combination of an electrically-controlled member, a switch-device for controlling the actuation of said member, electrically-controlled mechanism for opening and closing said switch device, electrically-controlled switch devices, an electrical circuit in which one of said electrically-controlled switch devices, and one of said electrically-controlled mechanisms for controlling the position of said first-named switch are interposed, means for closing said circuit, a second circuit in which the last-referred-to electrically-controlled mechanism and a portion only of the resistance in said first-named circuit, are interposed, a third circuit in which the other of said electrically-controlled switch devices and the other of said electrically-controlled mechanisms controlling the position of said first-named switch device, are interposed, means for closing said third circuit, a fourth circuit in which said last-referred-to electrically-controlled mechanism controlling said first-named switch device and a portion only of the resistance in said first circuit, are interposed, means actuated by the energization of said electrically-controlled switch devices, respectively, to break said first and third circuits, respectively, and to close said second and fourth circuits, respectively, and means actuated by the energization of said electrically-controlled mechanisms controlling the position of said first-named switch device, to break said second and fourth circuits, respectively. 115

6. The combination of an electrically-controlled member, a switch device for controlling the actuation of said member, electrically-controlled mechanisms for opening and closing said switch device, an electrically-controlled switch device, an electrical circuit in which one of said electrically-controlled switch devices and one of said electrically-controlled mechanisms controlling the position of said first-named switch device, are interposed, means for closing said circuit, a second circuit in which the last-referred to electrically-controlled mechanism and a por- 120

tion only of the resistance in said first-named circuit, are interposed, a short circuit in which the other of said electrically-controlled switch devices and the other of said 5 electrically-controlled mechanisms controlling the position of said first-named switch device, are interposed, means for closing said last-named circuit, a fourth circuit in which the last-referred-to electrically-controlled mechanism controlling said first-named switch device and a portion only of the resistance in said first circuit, are interposed, means actuated by the energization of said 10 electrically-controlled switch devices, respectively, to break said first and third circuits, respectively, and to close said second and fourth circuits, respectively, and a circuit-opening-and-closing device adapted to control all of said four circuits, said last-named 15 device being actuated alternately by said electrically-controlled mechanisms and operating when one of the latter is actuated to break the circuit through the latter and move to a position in which the circuit 20 through which the other of said electrically-controlled mechanism is operated, is closed at this point preparatory to the closing of the last-referred-to circuit.

7. The combination of a switch device, 30 an electrically-controlled element controlled by said switch-device, solenoid devices, means operated by said solenoid devices, respectively, for opening and closing said switch device, relay devices each formed of resistance elements of different resistances, an electrical 35 circuit in which both resistance elements of one of said relay devices and one of said solenoid devices, are interposed, means for closing said circuit, a second circuit in 40 which one only of the resistance elements of said last-referred-to relay devices and said last-referred-to solenoid device, are interposed, a third circuit in which the resistance elements of the other of said relay devices 45 and the other of said solenoid devices, are interposed, means for closing said third circuit, a fourth circuit in which one only of the resistance elements of said last-referred-to relay device, and said last-referred-to 50 solenoid device, are interposed, means cooperating with said relay devices and operating upon the actuation of the latter, respectively to break said first and third circuits and to close said second and fourth circuits, respectively, and a circuit-opening-and-closing device actuated in opposite directions by said solenoid devices and operating, when actuated by one of said solenoid devices, to break the circuit through the latter and to close the circuit at this point through the other of said solenoid devices preparatory to closing of the circuit through said last-named solenoid device.

8. The combination of a thermostat having a pair of relatively fixed contacts, and

a movable contact adapted to alternately engage said fixed contacts, an electrically-controlled member, a switch device for controlling the actuations of said member, electrically-controlled mechanisms for opening and closing said switch device, electrically-controlled switch devices, an electrical circuit in which one of the fixed contacts of said thermostat, one of said electrically-controlled switch devices, one of said electrically-controlled mechanisms controlling the position of said first-named switch device, and a contact of said thermostat, are interposed, a second circuit in which said last-referred-to electrically-controlled mechanism and a portion only of the resistance in said first-named circuit, are interposed, a third circuit in which the other of the fixed contacts of said thermostat, the other of said electrically-controlled switch devices, the other of said electrically-controlled mechanisms controlling the position of said first-named switch device, and a movable contact of said thermostat, are interposed, a fourth circuit in which said last-referred-to electrically-controlled mechanism controlling said first-named switch device and a portion only of the resistance in said first circuit, are interposed, and means actuated by the energization of said electrically-controlled switch devices, respectively, to break said first and third circuits, respectively, thereby breaking the circuit through the thermostat, and to close said second and fourth circuits, respectively.

9. The combination of a thermostat having a pair of relatively fixed contacts, and a movable contact adapted to alternately engage said fixed contacts, an electrically-controlled member, a switch device for controlling the actuations of said member, electrically-controlled mechanisms for opening and closing said switch device, electrically-controlled switch devices, an electrical circuit in which one of the fixed contacts of said thermostat, one of said electrically-controlled switch devices, one of said electrically-controlled mechanisms controlling the position of said first-named switch device, and a contact of said thermostat, are interposed, a second circuit in which said last-referred-to electrically-controlled mechanism and a portion only of the resistance in said first-named circuit, are interposed, a third circuit in which the other of the fixed contacts of said thermostat, the other of said electrically-controlled switch devices, the other of said electrically-controlled mechanisms controlling the position of said first-named switch device, and a contact of said thermostat, are interposed, a fourth circuit in which said last-referred-to electrically-controlled mechanism controlling said first-named switch device and a movable contact of said thermostat, are interposed, a fourth circuit in which said last-referred-to electrically-controlled mechanism controlling said first-named switch device and a portion only of the resistance in said first

circuit, are interposed, means actuated by the energization of said electrically-controlled switch devices, respectively, to break said first and third circuits, respectively, 5 thereby breaking the circuit through the thermostat and to close said second and fourth circuits, respectively, and means actuated by energization of said electrically-controlled mechanisms controlling the position 10 of said first-named switch device to break said second and fourth circuits, respectively.

10. The combination of an electrically-controlled member, a switch device for controlling the actuation of said member, electrically-controlled mechanisms for opening and closing said switch device, electrically-controlled switch devices, an electrical circuit in which one of said electrically-controlled switch devices and one of said electrically-controlled mechanisms controlling the position of said first-named switch device are interposed, means for closing said circuit, a second circuit in which said last-referred-to electrically-controlled mechanism and a portion only of the resistance in said first-named circuit, are interposed, a third circuit in which the other of said electrically-controlled switch devices and the other of said electrically-controlled mechanisms controlling the position of said first-named switch device, are interposed, means for closing said last-named circuit, a fourth circuit in which said last-referred-to electrically-controlled mechanism controlling said first-named switch device and a portion only of the resistance in said first circuit are interposed, and means actuated by the energization of said electrically-controlled switch devices, respectively, to break said first and third circuits, respectively, and to close said second and fourth circuits, respectively, and a circuit-opening-and-closing device adapted to control all of said 45 four circuits, said last-named device being actuated alternately by said electrically-controlled mechanisms and operating when one of the latter is actuated to break the circuit through the latter and move to a position in which the circuit through which the other of said electrically-controlled

mechanisms is operated, is closed at this point preparatory to the closing of the last-referred-to circuit by the operation of the said circuit-closing means.

11. The combination of a thermostat having relatively stationary contacts and a movable contact adapted to move into and out of engagement alternately with said stationary contacts, a switch device, an electrically-controlled element controlled by said switch device, solenoid devices, means operated by said solenoid devices, respectively, for opening and closing said switch device, relay devices, each formed of resistance elements of different resistances, an electrical circuit in which one of the stationary contacts of said thermostat, both of the resistance elements of one of said relay devices, one of said solenoid devices and the movable contact of said thermostat, are interposed, a second circuit in which one only of the resistance elements of said last-referred-to relay devices, and said last-referred-to solenoid device, are interposed, a third circuit in which the other stationary contact of said thermostat, the resistance elements of the other of said relay devices, the other of said solenoid devices, and the movable contact of said thermostat, are interposed, a fourth circuit in which one only of the resistance elements of said last-referred-to relay device and said last-referred-to solenoid device, are interposed, means operating with said relay devices and operating upon the actuation of the latter, respectively, to break said first and third circuits, thereby breaking the circuit through said thermostat, and to close said second and fourth circuits, respectively, and a circuit-opening-and-closing device actuated in opposite directions by said solenoid devices and operating when actuated, by one of said solenoid devices, to break the circuit through the latter and to close the circuit at this point through the other of said solenoid devices preparatory to the movement of the movable contact of the thermostat into engagement with the stationary contact thereof cooperating with the said last-referred-to solenoid device.

GEORGE I. LEONARD.
